IMPLEMENT BAR FOR EMBROIDERING MACHINES

Max P. Neubert, Teaneck, N. J., and Oskar Mueller, New York, N. Y., said Mueller assignor to said Neubert

Application March 28, 1936, Serial No. 71,400

4 Claims. (Cl. 112—83)

This application is a continuation in part of our application Serial No. 55,148, filed December 19, 1935.

This invention relates to embroidering machines or the like and more particularly to the implement bars such as needle bars, borer bars, etc., and means for movably supporting said bars.

As hitherto constructed each bar carries a single row of implements and is so mounted in the machine frame as to be capable merely of a horizontal reciprocatory motion, whereby the implements are caused to perform their embroidering operation. According to the embroidery design to be produced on the fabric these implements, as stitching needles, borers (or stüpfels) are spaced apart for the particular repeat determined by the design, for instance, 4/4, 8/4, 12/4, etc. At 4/4 repeat all implements on the bar, i. e., all needles or all borers, etc. are in use. If the design to be embroidered is such that first one repeat, then another repeat or perhaps a third are used, then when a change is to be made from one repeat to another, it is necessary to remove from the bar alternate needles or borers or alternate groups of needles or borers according to the particular repeat.

With modern embroidering machines which are from 10 to 14 yards long, each bar carries hundreds of such implements and it is quite a tedious work consuming sometimes days to remove or replace the implements in a bar in order to change the repeat. It is, of course, obvious that during such period the machine remains idle. Moreover, when a two or multi-colored design is to be produced, the change from one color to another also consumes considerable time as the threads of one color have to be cut off and removed from the stitching needles and threads of a different color rethreaded.

The object of this invention is to provide a construction whereby these drawbacks will be obviated and whereby it is possible to change the arrangement of the implements for the different desired repeats or colors within but a few minutes, and thereby considerably increase the efficiency of the machine and reduce the expense of operation.

Another object is to so mount the different implement bars in the machine that by a single operation the said bars can be alternately brought into and removed from operative position relative to the fabric frame.

The novel construction comprises a polygonal bar either of triangular, square, pentagonal,

hexagonal, octagonal or any other cross section, with means for removably attaching to each face of said bar a row of implements, so that the implements on each face of the bar may in advance be spaced according to the repeats or the colors desired. Thus, the implements projecting from one face of the bar may be spaced for 4/4 repeats, those projecting from another face may be spaced for 8/4 repeats, etc. Only the implements which project from the face directed at a right angle toward the vertically extending tambour frame are in operative position while the implements projecting from the other faces are in inoperative position at that time. This polygonal bar is so mounted in the machine frame that in addition to its horizontal reciprocating movement toward and away from the fabric which it carries out in its performance of the embroidering operation, it also is capable of being turned on its longitudinal axis in order to change the implements of one face to that of another of said polygonal bars. It will be seen that the change of the implements for a different repeat or different color can thus be accomplished very easily and quickly by a mere rotation of the bar around its longitudinal axis.

Furthermore, in order to avoid the necessity of bodily removing one kind of implement bar and replacing it by another kind, or the necessity of lowering or raising the tambour frame to the level of the operative implements, according to our invention, the different sets of implement bars are additionally so supported and interconnected that through a mere rotary motion one of the implement bars is raised into operative position while the other is lowered and vice versa.

In the accompanying drawing which constitutes part of this specification and in which similar reference characters denote corresponding parts:

Fig. 1 is a top plan view of our implement bar supporting device.

Fig. 2 is a sectional side elevation thereof showing the implement bars adjusted for boring operation.

Fig. 3 is a similar view showing the implement bars adjusted for stitching operation.

Figure 4 is a section on line 4—4 of Fig. 2.

Fig. 5 is a perspective view of a borer bar, and

Fig. 6 is a detailed top plan view of a part of the needle bar.

Referring more specifically to the drawing, 10 and 11 denote bars for supporting the needles N and borers B respectively, used in performing the embroidering operations. Each bar is of square 55

or other polygonal cross section and provided on each face with a longitudinal row of sockets to hold the implements.

As stated in our copending parent application, the sockets for the needle bar preferably consist of transversely extending and equidistantly arranged grooves, channels or hollows 10^a for the engagement of the tail ends of the needles N, the eyeletted ends of which are adapted to project laterally from the respective faces of the bar. Arranged parallel to and adjacent to each groove 10^a is a second groove 10^b to engage the downwardly projecting flange or bead 12^a of a clamping plate 12, one for each needle, which is adapted to extend over the tail end of the needle N when mounted in the groove 10^a, and which is tightened in position by a screw hold 13 working in a threaded bore 10^c of the bar. This construction enables the spacing of the needles on the several faces of the bar according to the particular repeat desired, as shown in Fig. 6.

The sockets of the borer (and/or stüpfel bar), may, as shown, consist of mere threaded bores 11^a to engage the threaded tail ends of the borers B, as shown in Fig. 5.

Each bar is formed with two or more cylindrical portions or journals 10', 11' (Figs. 2 and 3) at their ends or intermediate their ends to be rotatively borne in transversely extending arms 14, 15 respectively, fulcrumed at their rear ends, as at 14', 15', to brackets 16, 17 respectively. These brackets are fixed to horizontal transversal rods 18, 18' respectively, which are slidably borne in the machine frame F and which in well-known manner are operated to reciprocate alternately the needle bar and borer bar toward and away from the tambour frame T (indicated by dotted lines in Figs. 2 and 3) during the embroidering operation.

In order to enable the exchange of implements performing different functions in the embroidering operation, i. e., from boring to stitching and vice versa, without the necessity of bodily removing the respective bars or displacing the tambour frame, each of the bars 10 and 11 is additionally engaged at one end by a bifurcated lever arm 19, 20 respectively, the lever arm 19 being fulcrumed at 19', and arm 20 at 20' in a stationary part F' of the machine frame F. The two arms are operatively connected together by a link 21. The arm 19 has a rear extension 19' which may also be bifurcated for the engagement of a roller or pin 22 carried by a bellcrank 23 which may be operated in well known manner from a driven cam 24 adapted to be controlled either automatically from a jacquard (not shown) or otherwise.

In operation, when it is desired to use the boring implements or borers B, the arms 14, 15 carrying the bars 10, 11 are adjusted by turning them on their fulcrums 14', 15', so that the arm 15 of the borer bar 11 will extend horizontally, i. e., perpendicularly to the tambour frame T, while the arm 14 of the needle bar 10 will extend at an angle thereto in an upwardly directed and, therefore, in inoperative position (Fig. 2). After such adjustment the borer bar 11 itself may be turned on its longitudinal axis to bring the row of borers of the desired repeat into the horizontal or operative position.

If according to the design to be embroidered, a different repeat becomes necessary, the borer bar 11 can be turned on its longitudinal axis to bring the borers of the desired repeat into active posi-

tion. During the boring operation, the borer bar 11 is reciprocated horizontally, sliding in the slot of the forked end of the arm 20.

To change from boring to stitching, the arms 14, 15 are swung in the opposite direction, so that the arm 14 of the needle bar 10 extends perpendicularly to the tambour frame T, while the arm 15 of the borer bar 11 extends at an angle thereto in a downwardly directed position (Fig. 3). In this position the needle bar also may be turned on its longitudinal axis to bring the needles of the desired repeat into operative position.

The bars 10, 11 may be provided at their ends or any other suitable points with handles (not shown) whereby they may be conveniently turned on their longitudinal axes.

It will be seen that according to our invention, each implement bar is so supported relative to the tambour frame that it is capable of three independent motions, to wit, the reciprocatory motion imparted to it through cam mechanism controlled from the jacquard (not shown) for the performance of the particular embroidering function, the rotary motion around its longitudinal axis for its adjustment for the desired repeat and finally the implement bars may in unison be turned vertically for the exchange of one kind of implements for another.

Various modifications may be made in the construction without departing from the principle of our invention. We, therefore, do not wish to restrict ourselves to the details described and shown.

What we claim is:

1. In an embroidering machine having a vertically disposed tambour frame, a plurality of horizontally supported implement bars for different functions of the embroidering operation and interconnected means engaging said bars so that by a single operation said bars will be arcuately swung to be alternately brought into and out of operative position relative to said tambour frame.

2. In an embroidering machine according to claim 1 in which said means consist of bifurcated, interconnected, rocking arms and in which means are provided for rocking the latter in unison.

3. In an embroidering machine having a vertically disposed tambour frame, a plurality of horizontally supported polygonal implement bars, each carrying on its different faces differently spaced sets of implements for different functions of the embroidering operation, means for reciprocatorily supporting said bars to perform their operations, means for rotatively mounting said bars in said first named means for the exchange of the different sets of implements and means for so mounting said last named means as to permit the simultaneous adjustment in a vertical direction of the different bars to alternately bring either one of the latter into operative position relative to said tambour frame.

4. In an embroidering machine having a vertically disposed tambour frame, an implement bar of polygonal cross section bearing on each face sets of implements and reciprocatory means for supporting said bar so as to be rotatable around its longitudinal axis for its adjustment according to the set of implements desired and means for swinging said first named means arcuately into and out of operative position.
